DAVID C. KLINE, OF ROCHESTER, NEW YORK, ASSIGNOR TO THE PRITCHARD-STRONG COMPANY, OF ROCHESTER, NEW YORK.

GLOBE-HOLDING DEVICE FOR TUBULAR LANTERNS.

963,299.

Specification of Letters Patent.

Patented July 5, 1910.

Application filed July 21, 1905. Serial No. 270,643.

To all whom it may concern:

Be it known that I, DAVID C. KLINE, a citizen of the United States, and resident of Rochester, in the county of Monroe and 5 State of New York, have invented certain new and useful Improvements in Globe-Holding Devices for Tubular Lanterns, of which the following is a specification.

This invention relates to globe holding 10 devices for tubular lanterns, and consists in the mechanism hereinafter described and claimed.

In the drawings:—Figure 1 shows a side 15 elevation of a lantern embodying this invention, the parts being removed in order to more clearly exhibit construction, and showing the parts in a position in readiness for the release of the globe; and Fig. 2 is a slightly enlarged like view of a top portion 20 of the lantern, showing the parts in their position while holding the globe.

In the drawings, 1 is the oil pot; 2 is the gallery; 3 is the burner cone; 4 is the globe plate; 5 is the globe; 6 is the canopy tube; 25 7, 7 represent air tubes, connected at the bottom to the gallery 2 and at the top to the canopy tube 6; 8 is the canopy, which is perforated at the center, and is adapted to slide freely vertically upon the canopy tube 30 6 and to tilt with reference thereto. The canopy 8 is provided with the usual wire Irwin spring holder for the top of the globe, which, when the parts are in their normal position, presses the globe downward against 35 the globe plate 4. Side wires 9 are connected to the globe plate 4 in any suitable way, and extend upward to the canopy 8 to which they are connected. Near the canopy 8, each side wire 9 has a loop 10, 40 or other considerable curvature therein, whereby the wire is made the more flexible, and notwithstanding the rigid connection of the wire to the canopy 8, the loop or curvature above mentioned permits a freer tilting 45 of the canopy, and at the same time, on account of the elasticity of the side wires 9, tends to return the canopy to its normal horizontal position shown in Fig. 2.

Assuming that the device is without a 50 globe, the procedure in order to insert a globe is as follows:—The Irwin spring holder 11 is raised by means of its handle 12 until the pressure tilts the canopy 8 and

flexes the side wire 9. The greater part of the bending of the side wire will occur at 55 the loop or curvature 10 when such loop or curvature is employed. When the Irwin holder and the canopy are tilted to the position shown in Fig. 1, the globe 5 may be placed on the globe plate 4 and may be 60 tilted inward underneath the canopy, whereupon, on releasing the handle 12, the parts take the position shown in Fig. 2, returning the canopy 8 to its horizontal position and fitting the Irwin holder 11 upon the upper 65 end of the globe, whereby the globe is pressed firmly against the globe plate and held in place.

It is obvious that with the construction above described, namely, that in which the 70 upward movement of the spring catch 11 tilts the canopy 8, a smaller distance is required between the spring catch and the lower edge of the canopy in order to release the globe, and this smaller space between 75 the top of the globe and the canopy reduces the opening for inward air currents tending to blow out the flame. In other words, with this construction the opening between the top of the globe and the lower edge of 80 the canopy is much reduced from that heretofore employed. Further, the side wires 9 are rigidly fastened in the canopy 8 and in the globe-plate 4 and, being elastic, act as springs to return the canopy from the 85 tilted position shown in Fig. 1 to its normal position shown in Fig. 2; and further, the flexibility of the side wires, rigidly fastened in the globe plate and canopy, permit the tilting of the canopy tube and its 90 return to place.

The loop 10 has a curvature in the side wire and constitutes a portion thereof that is of greater flexibility than the remainder. By this means rigid side wires may be employed with a flexibility that is limited to one point therein. This construction prevents lateral shifting of the canopy as to the canopy tube, and avoids the employment of a construction such as an extended oblong 100 slot in the canopy, and a shifting cover to close the slot around the canopy tube.

What I claim is:—

In a globe holding device for lanterns, a lantern frame having a canopy tube, a 105 canopy having a perforation for said tube,

a globe plate, side wires rigidly connected to said canopy and to said globe plate, and having a loop therein constituting a portion of greater flexibility than the remainder, and a spring globe holder on said canopy, whereby the globe holder and the canopy may be tilted to release the globe

substantially without appreciable lateral movement of the canopy with reference to the canopy tube.

DAVID C. KLINE.
